(57) **CLAIM**

The ornamental design for a wheel lathe as shown and
described.

DESCRIPTION

FIG. 1 is a front perspective view from above of the claimed
wheel lathe;

FIG. 2 is a top view of the claimed design;

FIG. 3 is a bottom view of the claimed design;

FIG. 4 is a front view of the claimed design;

FIG. 5 is a left side view of the claimed design;

FIG. 6 is a right side view of the claimed design; and,

FIG. 7 is a rear side view of the claimed design.

Any portion of the article depicted in broken lines forms no
part of the claimed design.

1 Claim, 6 Drawing Sheets
